PARTIAL PRODUCT STRUCTURE

Loring Pickering Crosman, South Orange, N. J.,
assignor to Monroe Calculating Machine Company,
Orange, N. J., a corporation of Delaware

Application November 20, 1945, Serial No. 629,777

1 Claim. (Cl. 235—61)

1

The invention relates to an improved means for selecting and registering partial products in multiplying machines.

In prior decimal system machines of this type the graduation of the partial product plates representing the units and those representing the tens digits of the partial products related to a given multiplier digit have consisted of series of stepped faces of eight or nine steps each, with a corresponding extension of the plates in two of their dimensions. This, together with similar provision for the remaining multiplier digits, and the duplication of the entire partial product table in each denominational order of the machine, has resulted in the employment of an assembly of plates of considerable mass and extent. The present invention provides means for employing a lighter, more compact plate assembly, and it consists in the novel construction and combination of parts, as set forth in the appended claim.

In the accompanying drawings illustrating the invention:

Fig. 1 is a vertical section taken through the factor keyboard of a listing machine to which the invention has been applied.

Fig. 2 is a left side elevation showing various multiplication control devices.

Fig. 3 is an enlarged left side elevation of the factor value locking means and of certain multiplication control cams.

Fig. 4 is a vertical section taken through the parts lying forward of the keyboard.

Fig. 5 is a detail perspective view of a portion of the units feeler actuating means.

Fig. 6 is an axial section through the partial product plates.

Fig. 7 is a detail right side elevation of the partial product transmission means.

Fig. 8 is a section taken on line 8—8, Fig. 4.

Fig. 9 is a detail plan view of the tens feelers and associated parts.

Fig. 10 is a series of detail elevations showing the five partial product plates.

Fig. 11 is a timing diagram illustrating the movements of various parts.

The five partial product plates herein illustrated provide for the products involving the multiplier digits from 1 to 5. Co-pending application Serial No. 629,841, filed by Howard M. Fleming, of even date herewith, and entitled Multiplying machine shows means whereby these five plates may be used to control the registration of products involving all of the multiplier digits from 1 to 9, but since the means for ef-

2

fecting this result form no part of the present invention, they have not been shown in the present application. However, in so far as the disclosure of the Fleming application may be pertinent as providing for an advantageous application of the present invention in a complete machine, such disclosure is made of record.

Alternative arrangements, coming within the scope of the present disclosure, will be considered more conveniently in connection with the detailed description of structure.

Entering the factors

In accordance with above noted disclosure, 15 amounts set up by the digit keys 215 (Fig. 1) may be transferred to an accumulator 473, upon operation of the machine, by means of a series of differential actuators 610. These differential actuators are spring operated, and are normally 20 restrained by frame 616. Each actuator 610 is fulcrumed at 608, a forward arm thereof having segmental gear teeth for rotating an accumulator wheel and an upper arm being pivotally connected with a digit index bar 615. The actuators are 25 normally held under restraint of a series of column latches 214, each latch being releasable upon depression of any key 215 in the same column by means of a slide 213. Upon operation of the machine and consequent movement of the frame 616, 30 the released actuators will be rotated counterclockwise each until stopped by contact of a lug of the related index bar 615 with the stem of a depressed key.

The multiplicand is set up on keys 215, and 35 the partial product plates are adjusted accordingly during a non-add operation of the actuators 610. During this operation accumulator 473 is moved out of mesh with the actuator segments, and a cam 318 (Fig. 2) is rocked by a shaft 301, 40 to reciprocate frame 616 in known manner.

The setting movements imparted to the actuators 610 during the forward stroke of cam 318 are transmitted to related stop plates 506 (Fig. 1), loosely mounted upon a shaft 507 and held in 45 contact with the actuators by springs 508. At the end of this forward stroke the stop plates are locked in adjusted positions by engagement of a rotary bar 509 with graduated faces of said plates. Bar 509 is rocked into locking engagement with the stop plates 506 by contact of a projection 510 (Fig. 3) of cam 318 with a lug 511 of pivoted arm 512, contacting an arm 509' of said bar, the locking engagement being maintained during the return stroke of the cam by engagement of a spring latch 513 with lug 511. At

the end of the return stroke of the parts, latch 513 will be lifted by a pin 514 mounted in the cam, and bar 509 will be rocked to unlocking position by a spring 515.

During that portion of the non-add cycle in which the multiplicand value is locked in the plates 506, a series of feelers will be brought into contact with said plates, whereby the values will be entered in the partial product plates.

For this purpose a bail 528 (Fig. 4) is rocked clockwise, said bail lying in rear of a series of spring impelled segments 529, loosely mounted upon a shaft 530. Upon release from the restraint of bail 528, the segment springs 531 will rotate the segments clockwise until feelers 532, pivotally connected thereto, come into contact with studs 533 of the adjusted stop plates 506.

The segments 529 mesh with intermediate gear members 534, meshing in turn with gears 537, each rotatably connected to a series of five partial product plates 538 (Figs. 6, 7, 10), mounted upon a sleeve supported upon a shaft 539. Clockwise rotation of the related segments 529 will thus rotate the partial product plates 538, each series of plates a number of steps (from one to nine) in accordance with the multiplicand value set in the corresponding stop plate 506.

As shown, a partial product plate is provided to represent the products of each multiplier digit, and the multiplier is selected by moving the series of plates laterally, to bring the required plates opposite the feelers which control the registration. For this purpose, it may be noted, the intermediate gearing 534 is swung forward, out of mesh with the gears 537. Obviously, with a different arrangement of the values upon the partial product plates, a different method of multiplier selection might be employed.

Registering the partial products

The multiplication is effected by rotation of an operation control shaft 667 (Figs. 2 and 3) upon which are mounted a series of cams which act to determine the calculation and registration of the partial product values.

Cam 668 (Fig. 3) operates the units value feelers, this being the first operation effected during additive calculations (see diagram, Fig. 11). A spring urged cam follower 669 is rocked counter-clockwise by cam 668, said follower, through link 670 and bell-crank lever 671, rocking a shaft 673. Shaft 673 has link connection 672 with a pair of arms 675, supported upon shaft 674 (Figs. 4 and 7) and having pivotal connection 676 with a pair of hangers 677 (Fig. 5) engaging perforations of two spaced bars 678, riveted together to form a rigid frame. This frame has yieldable connection with the units feelers 679, 680, there being a pair of such feelers related to each accumulator wheel unit. Each yieldable connection comprises a link 681, pivotally connected with its feeler and having a slotted extremity engaging a notched portion of one of the bars 678, a spring 682 bearing against a shoulder of the link and against the bottom of the bar. Upon rocking movement of shaft 673 frame bars 678 will be depressed, and feelers 679, 680 will be rocked about their pivot 683, each pair into contact with the selected partial product plate 538 of its related group, the spring 682 yielding when such movement is interrupted by contact of a feeler with the plate.

Two units feelers are employed in each order, and their settings are combined to provide for a differential one to nine step counterclockwise rotation of the related auxiliary or multiplication

actuator segment 684, in order to reduce the number of graded steps of the partial product plates, with a consequent permissible reduction of diameter.

It will be noted that this reduction of diameter is further dependent, in the illustrated embodiment of the invention, upon the limitation of the tens value feelers to a travel of four steps, made possible by the employment of the semi-complemental multiplier arrangement set forth in the hereinbefore mentioned Fleming patent application. However, the same advantage would be obtained with a complete partial product table, representing values from 1 to 81, since the two feeler arrangement shown as applied to the units values might be duplicated for the tens.

The settings of the two feelers are combined as follows:

Feeler 679 has pin and slot connection with the outer end of a pivoted arm 685, mounted upon a plate 686 supported upon the auxiliary actuator shaft 687, arm 685 being provided with a stop lug 688 designed for contact by one of a series of graded stop shoulders of the actuator segment 684, the shoulder making contact being determined by the degree of clockwise adjustment of the feeler. The shoulders of the segment are so spaced as to provide for 0, 3, 6, or 7 steps of movement, controlled by four evenly graded steps of the partial product plate. Feeler 680 is provided with a stop lug 689 designed for contact with one of a series of three evenly graded stop shoulders of the plate 686, the shoulder making contact being determined by counter-clockwise adjustment of the feeler, controlled by three evenly graded steps of the partial product plate. Upon contact of the segment with stop 688 plate 686 will be carried counter-clockwise, against the tension of its spring 690, so that the pivotal support of arm 685 will be carried forward to allow for 0, 1 or 2 steps of movement of the actuator segment. Therefore, by combining the settings for 1 or 2 steps of movement with the settings for 3, 6 or 7 steps any of the digits from 1 to 9 may be registered.

The tens feelers 691 are operated through a shaft 695. Keyed to shaft 695 is a series of arms 696 (Figs. 4, 7, and 9) having yieldable drive connection by means of the transverse spring 697 with a series of stops 698, loosely mounted upon shaft 695 and having each pin and slot connection with a tens feeler 691. The stops and feelers are normally located by contact of the stops with overlying lugs of the arms 696. The rear ends of stops 698 are designed to be contacted each by one of a series of five graded stop shoulders of the actuator segments 684, in accordance with the contact of feelers 691 with one of a series of five graded steps of the partial product plates (see Plate 5x, Fig. 10), to provide for registration of the values 0, 1, 2, 3, 4, upon clockwise rotation of the segments. During these operations the partial product plates are held in set position by spring detents 699 (Fig. 4) engaging the gears 537.

The auxiliary actuator segments 684 are driven by a pair of complementary cams 720 (Fig. 3), through cam follower 721, link 722, arm 723 and shaft 724. Shaft 724 has yieldable drive connection with a series of segments 725 (Figs. 4, 7, 8), the connection being effected by a series of U-shaped plates 726, having each spline connection with the shaft and lugs upon its opposite arms normally engaging the opposite ends of a spring 727, said spring also normally engaging lugs of

two adjacent segments 725. This arrangement provides a yieldable drive of the segments upon rocking movement of shaft 724 in either direction from the normal position illustrated in Figure 4. Each segment 725 meshes with a pinion 728 having fixed connection with one of the auxiliary actuator segments 684, so that the latter segments will be driven against the feeler connections upon movement of shaft 724.

During each calculating cycle, the accumulator pinions 403 will be meshed with and unmched from actuator segments 684 under control of a cam 729 (Fig. 2). Cam 729 acts through cam follower 730 to rock an arm 731, fast with one arm of a toggle 10 which has connection with the accumulator shaft 472.

The successive actions effected by the calculation controlling cams may be traced on the diagram, Figure 11, as follows:

During an additive cycle of operation, cam 668 first operates the units feelers to position the stop lugs 688 and 689 (Figs. 4, 7) in accordance with the units values. Cams 720 then act to rotate the auxiliary segments 684 counter-clockwise, into engagement with lugs 688, in which position the segments will be held while cam 729 acts to move the accumulator pinions 403 out of mesh with the lister actuator segments 610 and into mesh with the auxiliary actuator segments 684 and while a cam (not shown) acts to rock shaft 695 and operate the tens feelers to position the stops 698 in accordance with the tens values. This is the position of the parts illustrated in Figure 7, the dot dash showing of segment 684, indicating a registration of nine and the fragmentary full line showing indicating a zero. Cams 720 will now act to rotate the segments 684 clockwise to their normal position, to register the units and beyond said position, into contact with the stops 698 to register the tens, a maximum of thirteen steps of movement. Cam 668 will now retract the units feelers and cams 720 will unmash the accumulator pinions from segments 684 and mesh them again with the lister actuator segments 610, during which time the segments 684 will be held stationary. Cams 720 will next return the auxiliary actuator segments 684 to and slightly beyond their normal position, to afford clearance with the tens stops 698, which are then restored by their cam. Finally, the segments 684 are moved through the true neutral position into their normal position of rest, in which clearance is provided with the units lugs 688.

Example

The operation of the partial product calculating mechanism above described may be illustrated by following through the actions involved

in the calculation of the previously noted example, 4×775 .

The partial product plates marked 4x in Figure 10 are brought opposite the feelers 679, 680, and 691.

Three of the partial product plate groups have been advanced to represent the multiplicand, the groups in the hundreds and tens orders seven steps and the units order group five steps. In 10 the hundreds order feeler 679 (Fig. 4) enters two steps in contacting the plate 538, positioning the lug 688 opposite the third shoulder inward from the periphery of segment 684, to represent the value six. Feeler 680 enters two steps, bringing 15 lug 689 opposite the outer shoulder of plate 686, and thus allowing two extra steps of counterclockwise movement of the segment, which, added to the six steps allowed by feelers 679, gives a total of eight steps to represent the units value 20 of the partial product 28. Feeler 691 enters two steps in contacting plate 538, providing for two steps of movement of the thousands segment 684. In the tens order the feeler actions are the same, except that the units and tens of the partial 25 product are registered in the tens and hundreds order, so that, in the hundreds order, segment, 684 is allowed eight steps of counterclockwise movement and, during the return or clockwise stroke will move eight steps to its neutral position 30 plus two steps beyond that position, giving a registering movement of ten steps. Finally, in the units order, where the partial product plates were advanced five steps, feelers 679 and 680 are held on the extreme outer surface of plate 538, to provide for contact of the outer shoulder of segment 35 684 with lug 688 and plate 686 is held against movement, so that no counterclockwise movement of segment 684 can occur. Feeler 691 however enters two steps, so that an additional two step movement of the tens order segment 538 is 40 provided for, representing the partial product 20. Thus during the calculating cycle, the four right hand segments 538 will register the values 2800, 280 and 20, which will be accumulated as 3100.

45 I claim:

In a multiplying machine having an actuator segment and a selectively settable partial product plate provided with two series of graded stop faces; a member settable to variably limit the extent of movement of the actuator segment, two 50 feelers each adjustable into contact with a selected stop face of its related series, and differential connections between the feelers and the settable member designed to transmit adjustable movement of one or alternatively of both said feelers to variably set said member in accordance with the setting of the partial product plate.

LORING PICKERING CROSMAN.
